UNITED STATES PATENT OFFICE.

MAHLON E. LAYNE, OF MEMPHIS, TENNESSEE.

WELL-SCREEN.

1,328,438.

Specification of Letters Patent. Patented Jan. 20, 1920.

Application filed April 9, 1917. Serial No. 160,588.

To all whom it may concern:

Be it known that I, MAHLON E. LAYNE, a citizen of the United States, residing at Memphis, in the county of Shelby and State 5 of Tennessee, have invented certain new and useful Improvements in Well-Screens, of which the following is a specification.

This invention relates to well screens for straining the water or oil at the bottom of 10 wells before it is pumped to the surface, and has to do, in general, with that class of screen known in the art as wire wound or wrapped screen, wherein a perforated casing or tubing has spirally wrapped thereon 15 a helix of screening wire. It has for its objects the provision of a screen of the character described, wherein the strands of the helix will be evenly and regularly spaced and firmly held in position and wherein the 20 space between wires will be absolutely free of any impediment to the inflow and circulation of the liquid, thereby securing a maximum of efficiency. More particularly, 25 it has for its object the provision of a screen, the wire of which presents in cross-section the shape of a section of a truncated cone and which I have termed a "keystone wire" in previous patents issued to me, and which has a depending portion or lug on the side 30 coming next to the casing adapted to project into a groove or thread thereon. The invention contemplates the provision of a wire-wrapped screen which combines the advantages of a keystone-shaped wire and of 35 a spiral groove or thread on the casing, all of which appearing more fully hereinafter.

The foregoing, together with such other objects as may hereinafter appear, or are incident to my invention, I attain by means 40 of a construction, the preferred embodiment of which I have shown in the accompanying drawings, wherein—

Figure 1 is a longitudinal section of a screen illustrating my improvement applied 45 thereto; and Fig. 2 is a side elevation show-

ing the general arrangement of the wire on the screen. The perforated casing or tube is designated by the numeral 7, the perforations by the numeral 8, and the wire by 9. The wire, it will be seen, is of the key- 50 stone shape above referred to, and is wound with the narrower face seated against the casing and with the wider face on the outside. The inner face 10 of the wire is made broad enough to prevent tipping to one side 55 or the other when wrapping the wire or when inserting the screen into the well, especially where the formations are very rough and hard, as, for instance, rock formations. The wire is preferably disposed on the 60 screen with its longer axis vertical to the surface of the screen. At the base of the wire is formed preferably at one side though not necessarily the projecting strip or continuous lug 11 adapted to fit into the groove 65 12. While wrapping the wire this projecting strip which fits into the groove 12 spaces the strands of the helix evenly and regularly and holds them firmly in place against movement longitudinally of the casing after 70 having been wound thereon.

I claim:—

1. In a well screen, the combination of a supporting frame, a helical groove formed thereon and a helix of screening wire wound 75 thereon, said wire having a flat base contacting with the surface of the supporting frame and having a projection extending into the groove.

2. In a well screen, the combination of a 80 supporting frame, a helical groove formed thereon and a helix of screening wire wound thereon, said wire having a flat base contacting with the surface of the supporting frame and having a projection at one side 85 thereof extending into the groove.

In testimony whereof, I have hereunto signed my name.

MAHLON E. LAYNE.
